UNITED STATES PATENT OFFICE

149,610

DESIGN FOR A CIRCULATING HEATER
CASING

Carl G. Björncrantz, Evanston, Ill., assignor to
Sears, Roebuck and Co., Chicago, Ill., a corporation of New York

Application June 22, 1946, Serial No. 130,933

Term of patent 14 years

(Cl. D81—19)

To all whom it may concern:

Be it known that I, Carl G. Björncrantz, a citizen of the United States and a resident of Evanston, in the county of Cook and State of Illinois, have invented a new, original, and ornamental Design for a Circulating Heater Casing, of which the following is a specification, reference being had to the accompanying drawing, forming a part thereof.

Fig. 1 is a front elevational view of the circulating heater casing embodying my new design.

Fig. 2 is a side elevational view thereof; and Fig. 3 is a top plan view of the same.

The rear of the casing is plain, and the side not shown is similar to side shown in Fig. 2.

I claim:

The ornamental design for a circulating heater casing, substantially as shown and described.

CARL G. BJÖRNCRANTZ.
